COMBINATION LAMP AND PLANT HOLDER

Lawrence J. Cianciolo, Milwaukee, Wis.

Application July 31, 1951, Serial No. 16,095

Term of patent 3½ years

(Cl. D48—20)

To all whom it may concern:

Be it known that I, Lawrence J. Cianciolo, a citizen of the United States, residing at Milwaukee, in the county of Milwaukee and State of Wisconsin, have invented a new, original and ornamental Design for a Combination Lamp and Plant Holder, of which the following is a specification, reference being had to the accompanying drawing forming a part thereof, and in which:

I claim:

The ornamental design for a combination lamp and plant holder, as shown.

LAWRENCE J. CIANCIOLI.
